GATE CLOSER

William A. Jackson, Jr., Harrison, Ark., assignor to Southern Precision Industries, Inc., Harrison, Ark., a corporation of Arkansas

Filed Mar. 7, 1968, Ser. No. 10,889

Term of patent 14 years

(Cl. D28—1)

Fig.1.

Fig.2.

Fig.3.

Fig.4.

Fig.5.

FIG. 2 is an end elevational view thereof;

FIG. 3 is a top plan view thereof;

FIG. 4 is an elevational view of the gate closer illustrating the end thereof opposite to that shown in FIG. 2; and

FIG. 5 is a side elevational view of the gate closer showing the side thereof opposite that shown in FIG. 1.

I claim:

The ornamental design for a gate closer, as shown.
